(57) **CLAIM**

The ornamental design for a turbo machine double blade and platform, as shown and described.

DESCRIPTION

FIG. 1 is a bottom, left, front perspective view of a turbo machine blade and platform showing our new design;

FIG. 2 is a bottom, right, front perspective view of the turbo machine blade and platform shown in FIG. 1; and,

FIG. 3 is a top, right, rear perspective view of the turbo machine blade and platform shown in FIG. 1.

Portions of the turbo machine blade and platform not shown in the drawings form no part of the claimed design.
